GRADE LEVEL HOUSING FOR TELEPHONE,
TELEVISION, SIGNAL AND ELECTRIC POWER
CABLES

William H. Channell, 620 W. Foothill Blvd.,
Glendora, Calif. 91740

Filed July 29, 1968, Ser. No. 12,952

Term of patent 14 years

Int. Cl. D13—03
U.S. Cl. D26—5

FIGURE 1 is a top plan view of a grade level housing for telephone, television, signal and electric power cables, showing my new design.

FIGURE 2 is a side elevational view thereof; and,
FIGURE 3 is a bottom plan view thereof.

I claim;

The ornamental design for a grade level housing for telephone, television, signal and electric power cables, substantially as shown.
